CLAIM

The ornamental design for a gummy bear, substantially as shown and described.

DESCRIPTION

FIG. 1 is a front, top and left side view of a gummy bear showing my new design;

FIG. 2 is a front elevation view thereof;

FIG. 3 is a left side elevation view thereof, the right side elevation view being a mirrored image thereof;

FIG. 4 is a top plan view thereof; and,

FIG. 5 is a bottom plan view thereof.

The shade lines in the Figures show contour and not surface ornamentation.
